UNITED STATES PATENT OFFICE.

HARRY H. CHINSKY AND EMIL HONSTETTER, OF BROOKLYN, NEW YORK.

DESIGN FOR A SPARK-PLUG.

58,215.

Specification for Design. Patented June 28, 1921.

Application filed April 10, 1920. Serial No. 373,015. Term of patent 3½ years.

To all whom it may concern:

Be it known that we, HARRY H. CHINSKY and EMIL HONSTETTER, citizens of the United States, residing at Brooklyn, in the county of Kings and State of New York, have invented a new, original, and ornamental Design for Spark-Plugs, of which the following is a specification, reference being had to the accompanying drawing, forming part thereof.

The figure is a side elevational view of a spark plug, showing our new design.

We claim:

The ornamental design for a spark plug, as shown.

HARRY H. CHINSKY.
EMIL HONSTETTER.
